United States Patent Office

Des. 190,325
Patented May 16, 1961

190,325

SAFETY RAZOR

Joseph Pepin, 8846 Stewart Ave., Los Angeles, Calif.

Filed Sept. 6, 1960, Ser. No. 62,026

Term of patent 3½ years

(Cl. D22—3)

FIG. 1.

FIG. 2.

FIG. 3.

FIG. 4.

FIG. 5.

Fig. 1 is a perspective view of a safety razor, showing my new design;

Fig. 2 is an elevation of one side thereof, the opposite side having the same appearance;

Fig. 3 is an end elevation thereof, the opposite end having the same appearance;

Fig. 4 is a top plan view thereof; and

Fig. 5 is a bottom plan view thereof.

I claim:

The ornamental design for a safety razor, substantially as shown and described.
